UNITED STATES PATENT OFFICE.

WILLIAM D. FERRIS, OF STERLING, ILLINOIS, ASSIGNOR TO FRANTZ MANUFACTURING CO., OF STERLING, ILLINOIS, A CORPORATION OF ILLINOIS.

GARAGE-DOOR CONSTRUCTION.

Application filed May 21, 1928. Serial No. 279,381.

This invention relates to garage doors, or doors for other buildings, of that kind in which one or more sliding sections and a swinging section are hinged together and supported for sliding movement on an overhead track, which ordinarily has one straight section above the doorway, another straight section on the side of the building, and a curved section connecting the two straight sections together, whereby the door structure is adapted to slide or move out of the doorway and around the curve into a position at the side of the building.

Generally stated, the object of the invention is to provide a novel and improved hanger whereby the swinging door section has a swivel support adapted to travel on said track, whereby the swinging door section is always fully supported in all positions thereof, is prevented from sagging, and is prevented from swinging around while the door structure as a whole is being opened.

It is also an object to provide certain details and features of construction and combinations tending to increase the general efficiency and the desirability of a sliding and swinging door structure of this particular character.

To the foregoing and other useful ends, the invention consists in the matters herein-after set forth and claimed, and shown in the accompanying drawings, in which,—

Fig. 1 is an inside elevation of a door structure embodying the principles of the invention, showing certain portions broken away for convenience of illustration.

Fig. 2 is an enlarged detail section on line 2—2 in Fig. 1.

Fig. 3 is an enlarged horizontal section on line 3—3 in Fig. 1.

Fig. 4 is a horizontal sectional view showing the front wall of the garage, and also the side wall thereof, in horizontal section, and showing the track and the door structure in plan view.

Fig. 5 is an enlarged front elevation of the special hanger for the swinging door, showing adjacent portions of the track and door.

Fig. 6 is a vertical section on line 6—6 in Fig. 5.

As thus illustrated, the building has a front wall 1 provided with the usual or any suitable doorway 2, and has a side wall 3 at 55 right angles thereto. Inside the building, the track for supporting the door structure comprises the horizontal straight portion 4 suitably mounted over the doorway, the straight portion 5 suitably mounted on the 60 side wall of the building, and the curved section 6 connecting the two straight track sections together. The said track can be of any suitable character, but is preferably a combined sheet-metal housing and track, as 65 shown more clearly in Figs. 5 and 6 of the drawings.

The two sliding door sections 7 and 8 are hinged together by upper and lower hinges 9 (the lower hinges not shown), and the 70 swinging door section 10 is hinged to the sliding section 8 by upper and lower hinges 11 (the lower hinges not shown), and the three door sections are supported by hangers 12, of any suitable character, on the said 75 track, all in such a manner, as shown, that the door sections can slide or travel around the curve 6 and finally be supported in fully open position by the track section 5, in the well known manner.

To prevent the swinging door section from being a dead weight on the hinges 11, and to keep it from sagging, a special hanger 13 is provided to travel on the track like the other hangers, and this hanger 13 85 has a swivel rod connection 14 with the door section 10, as shown. This rod has its horizontal portion pivoted at 15 on the lower end portion of the hanger 13, while the vertical portion 16 of said rod is swiveled in 90 the bearing 17 of the bracket plate 18 on the adjacent upper corner portion of the swinging door section. A spring-pressed catch 19, of any suitable character, is pivoted on the swinging door section in position to slide under the upper horizontal portion of the rod 14, and then spring upward into latching position when the swinging door section 10 is swung inward, thus latching the swinging door section in position on 100

its special hanger. When this has been done, the entire door structure is in condition to slide or travel around the curve 6 and into open position on the track 5, thus 5 fully opening the doorway. The swinging section 10 being latched in position on its special hanger 13, it follows that this door section cannot swing around or interfere, or get in the way, when the door structure 10 is open, this swinging door section forming the leading section when the sections are moved on the track around the curve and into fully open position.

When the door structure is to be closed, 15 the entire structure is rolled on the wheels of the hangers, around the curve 6 and back into position to close the doorway. Then a pull on the chain or other connection 20, which is fastened at its upper end to the 20 catch 19, will pull the catch downward and out of engagement with the rod 14, thus permitting the swinging section 10 to be moved or swung into fully closed position in the plane of the two sliding door sections. 25

The plate 18 preferably has an upper projecting portion 21 that slides over and bears upon the upper horizontal portion of the rod 14 when the swinging door section 10 30 is latched on its special hanger in the manner described, whereby the weight of the door section 10 is imposed on the rod 14 at a point closer to the pivot 15 than would be the case if the bearing 17 was relied upon 35 at such time to alone support the door section 10 on the pivot 15 of the special hanger, thus very firmly keeping the swinging door section 10 in position to move straight ahead edgewise during the opening movement of 40 the door structure as a whole.

It will be seen that a portion 22 of plate 18 serves as a stop to limit the swing of the arm 14 under the overhanging shoulder 21, as shown in Fig. 2 of the drawings.

45 While it is desirable to use the invention in connection with a swinging door section 10 that forms the leading section of a series of sliding door sections, it will be understood that some features of the invention 50 may be used in other ways, and on other doors, without departing from the spirit of the invention.

Moreover, it will be understood that the track section 5 in practice is long enough 55 to accommodate all the door sections thereon, so that the doorway will be fully open when the door structure is in position at one side of the building.

Again, it will be seen that the swinging 60 door section 10 only swings inward a distance sufficient to latch to the special hanger 13, in position to lead the other door sections around the curve. It does not, in other words, as shown and described, open far enough to permit entrance through the

doorway. Entrance is, therefore, obtained by sliding the door structure far enough to one side, either partially or fully around the curve 6, so that entrance is between the section 7 and the other side of the doorway. 70 Suitable handles (not shown) can be applied to the outer sides of the door sections to assist in opening the door structure. In addition, any kind of locking or latching means (not shown) may be employed for 75 locking or latching the entire door structure in closed position, if such is necessary or desirable.

Without disclaiming anything, and without prejudice to any novelty disclosed, what 80 I claim as my invention is:

1. Sliding and swinging door construction comprising a track having two straight sections disposed at an angle to each other, with a curved track section connecting together the said two straight sections, one or more sliding door sections provided with hangers adapted to travel on said track, a swinging door section hinged to a sliding door section, an additional hanger mounted 90 to travel on said track, a horizontally disposed arm pivoted at one end to swing horizontally on the lower end portion of said additional hanger, and a vertical swivel connection between the other end of said arm 95 and the adjacent upper corner portion of the swinging door section, permitting said swinging door section to swing inward a distance from its closed position, whereby the swinging section is supported against 100 sagging in all positions thereof, permitting the entire door structure to move out of the doorway and around the curve into a fully open position at the side of the building. 105

2. A structure as specified in claim 1, having a catch on the swinging door section to engage said arm and prevent said arm from swinging about its swivel connection with the swinging door section while the door structure is moving into open position. 110

3. A structure as specified in claim 1, having a catch on the swinging door section to engage said arm and prevent said arm from swinging about its swivel connection with the swinging door section while the door structure is moving into open position, together with manually operable means for disengaging the catch from said arm when the door structure is moved into closed position, permitting said swinging door section to then swing outward into closed position. 115

4. A structure as specified in claim 1, said swinging door section forming the leading section when the door structure travels 125 around the curve into open position.

5. Door construction comprising a swinging door, an overhead track, a hanger mounted to travel on said track, supporting one upper corner position of said door, a 130

horizontally disposed arm pivoted on said hanger at one end and swiveled on said door at its other end, means including a stop limiting the swing of said arm toward the door, when the door is swinging inward from closed position, limiting the inward swing of the door, and a hanger on said track to support the other upper corner of said door.

5 6. A structure as specified in claim 5,
10 having a catch on said door to engage and hold said arm against said stop, together with manually operable means for disengaging the catch from said arm.

15 7. A structure as specified in claim 5,
comprising a projection disposed on said door in position to slide over and rest upon said arm to impose the weight of the door on the arm at a point nearer its pivot on said hanger.

20 20 Specification signed this 19th day of May,
1928.
